US0D1108863S

(12) **United States Design Patent** (10) Patent No.: **US D1,108,863 S**
(45) Date of Patent: ** Jan. 13, 2026

(54) **MASSAGE CHAIR**

(71) Applicant: **CERAGEM CO., LTD.**, Cheonan-si (KR)

(72) Inventors: **Yeon Soo Kang**, Seoul (KR); **Jong Oh Lee**, Anyang-si (KR); **Jung Hyun Jo**, Anyang-si (KR)

(**) Term: **15 Years**

(21) Appl. No.: **35/521,176**

(22) Filed: **Jun. 7, 2023**

(80) **Hague Agreement Data**

Int. Filing Date: **Jun. 7, 2023**

Int. Reg. No.: **DM/229998**

Int. Reg. Date: **Jun. 7, 2023**

Int. Reg. Pub. Date: **Jun. 7, 2024**

(30) **Foreign Application Priority Data**

Feb. 20, 2023 (KR) 30-2023-0006129
